Inventor

John Gondek

UNITED STATES PATENT OFFICE.

JOHN GONDEK, OF ST. PAUL, MINNESOTA.

PRINTING APPARATUS.

Application filed March 17, 1920. Serial No. 366,586.

To all whom it may concern:

Be it known that I, JOHN GONDEK, a citizen of the United States, and a resident of St. Paul, in the county of Ramsey and State 5 of Minnesota, have invented certain new and useful Improvements in a Printing Apparatus, of which the following is a specification.

One object of my invention is to provide 10 in a printing apparatus means by which inequalities in the printing faces of the type are compensated for, thereby making an even print and eliminating the hand-make-ready that is ordinarily required, and thus 15 provide a method for all grades of commercial and color printing done on a cylinder or rotary type press.

Incidental objects are to provide a composition covering for the first transfer cylinder of unique construction and also provide the second transfer cylinder with a covering which is interchangeable with the covering of the feed cylinder.

In the drawing Figure 1 is a side elevation 25 of a printing press showing the bed, cylinders and actuating gear. Figure 2 is a section through the printing, transfer, and feed cylinders.

As shown in the drawings the frame work 30 A supports a slidable type bed 2 in the customary fashion, and journaled above the type bed is a horizontally disposed cylinder B which receives the printing impressions from the type in the type bed.

The cylinder C mounted parallel to the cylinder B and likewise journaled in the frame co-acts with the cylinder B to receive the impressions therefrom and constitutes 35 the printing cylinder.

The feed cylinder D which is likewise 40 parallel to the cylinder B is also journaled in the frame and co-acts with the printing cylinder C. The cylinders C and D preferably make three revolutions to four revolutions of the cylinder B, and the coverings on all of the cylinders are fastened with clamps and reels as is the general practice on such presses.

The general construction and operation of 50 the machine is similar to that disclosed in my Patent 1,347,505, July 27, 1920, entitled Printing apparatus, and only such parts of the apparatus as have to do with my invention are shown and described, as all of the

rest of the mechanism is perfectly familiar 55 to all those skilled in the art.

The cylinders B, C and D and the type bed 2 are operated from the drive shaft E through the gearing 5 in the customary manner. 60

The cylinder B is provided with a gear 6 which comes into engagement with the gear rack 7 on the bed 2 while the bed is traveling in one direction in the process of taking a print from the type and is then partly out 65 of engagement with the gear on the cylinder C.

When the bed is traveling in the opposite direction the cylinder B is raised from operative contact with the rack 7 and comes 70 into operative engagement with the gear on cylinder C through means not shown as any means for accomplishing this can be used and will be readily understood by those skilled in the art, and as this particular action has nothing to do with the invention it 75 is not further described or shown.

When the cylinder B is thus in operative relation with the cylinder C it transfers the impression on to the second transfer cylinder from which the print is taken on the paper on feed cylinder D. 80

The cylinder B has a covering substantially a half-inch in thickness which is composed of a suitable material such as burlap 85 1 on which is cast a heavy layer of preferably $\frac{7}{16}$ of an inch in thickness of specially prepared and comparatively soft yielding printers' roller material 3.

On this in turn is cast a fine layer preferably $\frac{1}{16}$ of an inch in thickness of specially prepared and perfectly smooth printers' roller material 3' which receives the impression from the type. 90

The depression in the roller is about a 95 half-inch in thickness to allow for this thick coating because if only material of $\frac{1}{16}$ of an inch in thickness was used for instance, it would not give without great pressure and would not spring back into place without 100 leaving an indenture in the surface. On the other hand with the thick covering I provide I obtain a yielding material which will give under very light pressure and will spring back into place without leaving any 105 indentures in the face.

It is important that this material as I have described it is cast into one piece and

not separate layers, because when pressure is applied to the hard surface the soft bed will recede and spring back with the surface free from any indenture as would appear if 5 separate layers were used.

As the top covering has a hard dull finish without the hardness and glazed face of celluloid it requires very light pressure to take an impression from the type and very 10 light pressure to transfer the impression to the second transfer cylinder, thereby eliminating every possibility of the type sinking into the printing surface or causing the surface to stretch or heat in the operation.

With this construction any amount of 15 pressure can be applied to the paper and the process permits a greater volume of ink to be taken. This ink will not be absorbed or deadened but will be transferred to 20 another surface in greater volume.

The printing cylinder C to which this impression is transferred has a hard covering of specially prepared printers' roller material 4 and this covering is interchangeable 25 with the covering on the feed cylinder D to which the paper is fed. The covering of the feed cylinder D as shown in the drawing is a metal 8 such as zinc and this in turn is interchangeable with the covering of the transfer cylinder C.

Where a dull print is wanted the second transfer cylinder C may be provided with a rubber blanket, and on some grades of printing the best results are obtained by the 30 use of zinc on this cylinder, in which case rubber would be used on the feed cylinder D.

When the type and cuts used are of positive face and also on double end and rotary 35 press, the feed cylinder D may be dispensed with and the cylinder C becomes both the printing and feed cylinder.

The art of make-ready as in general use is not scientifically correct and at best is 40 only a makeshift—a sort of hit and miss proposition that is extremely expensive. In the type press as now in general use, the print is taken from type and cuts directly 45 on to the paper. Accordingly it requires great skill and time to get required results and no matter how true the type, cuts and 50 press may be, satisfactory printing cannot be done without a make-ready. The reason is that all type and cuts are not of the same height and the bed of the press will 55 not remain true under great pressure. A heavy face or cut requires more pressure than light face type and cuts and all paper is more or less porous.

To illustrate this more clearly consider 60 a period or a very fine line and it will be realized that very little pressure is required to print this item, but a solid, say an inch square, will require many times more pressure, and if such a solid is placed together 65

with the period or fine line and given even pressure the one will have too much and the other not enough ink. This of course also applies to conditions where there are 70 solids in fine lines.

The grades of printing for which this press is designed require the construction of a press that will register perfectly in the two operations, that of the co-action of the type bed and the first transfer cylinder B 75 and the co-action of the first and second transfer cylinders.

To successfully accomplish this the first transfer cylinder should be alternately carried by the type bed and by the cylinder 80 C which is in contact with it, both being operated through the medium of gear 5, thereby assuring a perfect register.

While I have described my invention and illustrated it in one particular design, I do. 85 not wish it understood that I limit myself to this construction, as it is evident that the application of the invention may be varied in many ways within the scope of the following claims.

I claim—

1. Means for printing comprising a cylinder, a depression for said cylinder, a yielding printers' roller material covering for said cylinder, a relatively hard outer surfacing of printers' roller material for 90 said covering, a printing cylinder in engagement with said first cylinder and a feed cylinder in engagement with said second cylinder.

2. In a printing apparatus of the class described, a transfer cylinder having a yielding surface of printers' roller material, a thin relatively hard sheet of printers' roller material covering said surface and a transfer cylinder arranged in co-operation with said transfer cylinder.

3. In a printing apparatus of the class described, a first transfer cylinder having a covering, a second transfer cylinder having a relatively hard sheet of printers' roller material covering said cylinder and arranged in co-operation with said first transfer cylinder, a feed cylinder having a covering the said relatively hard sheet of 110 printers' roller material covering being interchangeable with the said feed cylinder.

4. In a printing apparatus of the class described, a feed cylinder having a smooth surface covering of metal, a first transfer cylinder, a second transfer cylinder, a covering for said second transfer cylinder, said last named covering and said metal covering being interchangeable.

5. In a printing apparatus of the class described, comprising a transfer cylinder, a yielding printers' roller material covering said cylinder, a hard outer surfacing of printers' roller material for said cover- 120

ing, and a feed cylinder having a relatively hard sheet of printers' roller material covering, arranged in co-operation with said cylinder, to print from positive face type and 5 plates.

6. In a printing apparatus of the class described, a movable type bed, a first transfer cylinder to receive impressions from

the bed, a second transfer cylinder to receive impressions from the first cylinder, 10 means for rotating the first transfer cylinder alternately from the movable type bed and from the second transfer cylinder, and driving gears between the bed and second transfer cylinder.

JOHN GONDEK.
